UNITED STATES PATENT OFFICE.

TOIVO PELTOLA, OF MARQUETTE, MICHIGAN.

ROTARY SEWER CLEANER.

Application filed August 7, 1922. Serial No. 580,084.

The purpose of this invention is to provide an improved machine for cleaning out large pipes or conduits such as sewer pipes, when they become blocked or their walls become more or less incrusted with solid matter. It consists in certain features and elements of construction and their combination as hereinafter described and shown in the drawings and as indicated by the claims.

In the drawings:

Figure 1 is a top plan view of a machine embodying this invention.

Figure 2 is a side elevation of the same.

Figure 3 is an axial section of the rotor and its bearings, with the cutting blades removed.

Figure 4 is a fragmental side elevation showing the mode of attachment of the cutting blades to the rotor hubs.

Figure 5 is a detail section taken as indicated at line 5—5 on Figure 4.

Figure 6 is a detail view partly in section, of an adjusting device for the supporting wheels.

Figure 7 is a transverse section of the nozzle casting taken as indicated at line 7—7 on Figure 1.

Figure 8 is a detail section of one of the cutting blades taken as indicated at line 8—8 on Figure 4.

Figure 9 is a transverse section taken as indicated at line 9—9 on Figure 1.

As shown in the drawings, this machine comprises a metallic nozzle adapted to be attached at the end of a hose providing a supply of water under pressure, and a rotor in the nature of a turbine wheel positioned at the discharge port of the nozzle to be rotated by the flow of water therefrom. The wheel or rotor carries a number of arched blades whose path of rotation on the wheel is substantially spherical, so that the blades travel tangent or nearly tangent to the walls of the pipe or conduit, and operate to cut away material incrusted thereon, while the water discharge from the turbine wheel serves to flush out this material and clear the pipe. In the drawings, the wheel or rotor is shown at 1, mounted in supporting bracket arms 2, which extend forwardly at both sides of the nozzle casting 3, thus forming a yoke in which the wheel revolves. Arched away from the axis of the wheel 1, but secured to its periphery and to its hubs, are the cutting blades 4

and 5, the former being made with serrated or saw-tooth edges as seen in Figures 2 and 4, and the latter having smooth knife edges.

It may be understood that the dimensions of the wheel 1 and arched blades 4 and 5 will be such that the apparatus may fit closely, but not too snugly within a sewer pipe of standard size, and where several sizes of pipe are employed, a plurality of cleaners of different dimensions may be provided, one for each size of pipe. In operation, the device is carried down in a manhole and introduced with the rotor, or wheel end forward, into the pipe to be cleaned. For supporting it upon the lower side of the pipe, there are provided small wheels or rollers 6 at the forward end of the nozzle casting 3, and slightly larger wheels 8 at the rear end of said casting, journaled on studs or bolts 9, as seen in Figures 1 and 2. The rear end of the nozzle 3 is threaded at 13 for attachment of the water supply hose, and the hose itself may serve for steering and advancing the machine into the pipe at the start. However, when once fairly entered, the machine will tend to propel itself by frictional engagement of the cutting blades and rotor wheel 1 with the bottom of the conduit; to insure such engagement, the forward carrying wheels or rollers 6 are provided with a limited vertical adjustment hereinafter more fully described.

The periphery of the wheel 1 is formed with a series of shallow pockets, each terminating at one end in a transverse wall or abutment 10, which receives the impact of the water flowing from the nozzle 3 and thus causes the wheel to be rotated. The cutting blades 4 and 5 are each firmly secured to the peripheral portion of the wheel by screws 11, and the forward ends of the yoke members 2 are sharpened at 12 so that they shall not oppose the advance of the machine, but shall rather assist in the removal of the incrystation on the walls of the pipes. The forward end of the nozzle casting 3 is formed with an overhanging rib portion 17 shrouding the rear side of the wheel 1 above the level of its axis of rotation, and discharge port 18 of the nozzle is located opposite this portion of the wheel, so as to cause rotation of the upper side of the wheel forwardly, and thus incidentally tend to feed the entire machine forwardly in the pipe.

The end portions of each of the blades 4 and 5 are securely attached by screws 19 to the end surfaces of the hubs 20 formed integral with the wheel 1. Preferably said hubs enclose ball bearings indicated at 21 in Figure 3, so that the wheel shall be freely rotatable upon its axle, whose threaded end portions 22 are screwed directly into the bracket arms 2 as shown. This provides a simple and exteriorly smooth construction; it may be understood that after assembly of the wheel with its axle and supporting bracket arms 2, said arms are mounted against the sides of the nozzle casting 3, and are fastened in place thereon by suitable bolts or screws 7.

As indicated in Figure 7, it is found preferable to overbalance the nozzle casting 3, making it heavier at the lower side and of thinner cross section at the upper side, so that the additional weight below the axis of the nozzle may assist in keeping the tool upright in the conduit, thus insuring that its weight shall be always supported on its wheels 6 and 8.

It will be evident that after exerting its force upon the abutment surfaces 10 of the wheel 1, the water discharged through the port 18 of the nozzle will be released at the forward side of the wheel, where it may serve for softening and loosening the incrusting material, and also for flushing away the solid matter as it is cut off by the blades 4 and 5. Where the pipe is wholly choked by a plug, the flushing water may flow back past the nozzle 3 and connected hose, these parts being of considerably less cross section than the pipe itself; but where the incrustation is limited to the walls of the pipe, the flushing water may flow forwardly ahead of the machine, unless it happens that the pipe inclines in the opposite direction.

For adjusting the wheel 1 with respect to the pipe or conduit to insure traction, I prefer to mount the carrying wheels or rollers 6 upon oblique axes, as shown in Figure 9, supporting them on swinging members 15^a pivotally attached to the nozzle casting 3 at 15^b. The lower ends of the members 15^a engage trunnions of cross member 15, which is threaded to receive the threaded end 14^b of the adjusting rod 14, shown in Figures 4 and 6. The rod 14 is formed with flanges

or shoulders 14^a, restricting it against longitudinal movement in a stirrup 16 at the rear end of the nozzle casting 3. The end of the rod 14 is bent into an eye to provide a handle for rotatively adjusting it so as to swing the members 15^a backwards and forwards for altering the vertical position of the rollers 6.

It may be understood that at any stage in the operation the entire machine may be withdrawn from the pipe or flue simply by pulling back the hose attached to the threaded part 13.

I claim:

1. In a machine for cleaning the inner surface of a pipe or conduit, a fluid supply pipe a wheel or rotor attached thereto and mounted for rotation about an axis substantially perpendicular to that of the conduit, said fluid supply pipe being arranged to extend longitudinally of the conduit with a nozzle for discharging fluid from said pipe against the periphery of the wheel for driving it, said wheel being formed with laterally extending hubs and one or more scraper blades arched over the wheel with both ends of each blade secured to said hubs. 80

2. In the combination defined in claim 1, said arched blades being curved in planes transverse to the plane of the wheel and being connected to be driven by the wheel so as to describe a substantially spherical path 85 as they revolve.

3. In a machine for cleaning the inner surface of the pipe or conduit, a fluid supply pipe a wheel or rotor attached thereto and mounted for rotation about an axis substantially perpendicular to that of the conduit, said fluid supply pipe being arranged to extend longitudinally of the conduit with a nozzle for discharging fluid from said pipe against the periphery of the wheel in substantially tangential relation, said wheel being uncovered at the side opposite the nozzle for releasing said fluid into the conduit, the wheel being formed with laterally extending hubs and one or more scraper blades 100 arched over the wheel with both ends of each blade secured to said hubs. 95

In testimony whereof, I have hereunto set my hand at Marquette, Michigan, this 31st day of July, 1922.

TOIVO PELTOLA.
